UNITED STATES PATENT OFFICE

THOMAS ETTER AND JOHN L. DUNN, OF PHILADELPHIA, PENNSYLVANIA

DESIGN FOR A PERFORATED EDIBLE

Application filed June 10, 1929. Serial No. 31,620. Term of patent 14 years.

To all whom it may concern:

Be it known that we, THOMAS ETTER and JOHN L. DUNN, residing at Philadelphia, in the county of Philadelphia and State of Pennsylvania, have invented a new, original, and ornamental Design for Perforated Edible, of which the following is a specification, reference being had to the accompanying drawing, forming a part thereof.

Figure 1 is a plan view of a perforated edible, showing our new design.

Fig. 2 is a section taken on line 2—2 of Figure 1.

We claim:

The ornamental design for a perforated edible, as shown.

THOMAS ETTER.
JOHN L. DUNN.
